UNITED STATES PATENT OFFICE.

HENRY S. CRAUS, OF MOUNT VERNON, ASSIGNOR TO JOHN MENAHAN & CO., OF NEW YORK, N. Y.

DESIGN FOR A PURSE OR BAG FRAME.

SPECIFICATION forming part of Design No. 18,477, dated July 24, 1888.

Application filed May 25, 1888. Serial No. 273,083. Term of patent 7 years.

To all whom it may concern:

Be it known that I, HENRY S. CRAUS, of Mount Vernon, in the county of Westchester and State of New York, have invented a new and original Design for Purse or Bag Frames, of which the following is a specification, reference being had to the accompanying drawing, forming part thereof, in which the figure is a perspective view of my newly-designed frame for purses, hand-bags, and the like.

The leading feature of my design consists of raised and depressed figures on the face of a U-shaped purse or bag frame, in imitation of the heel and toe calks, nail-heads, and nail-grooves of a common horseshoe, whereby the frame will be given the usual appearance of a horseshoe.

In the drawing, A is a U shaped purse or bag frame; B, a raised figure on top of the face of the same in imitation of the toe-calk of a horseshoe; C, raised figures in imitation of the heel-calks of a horseshoe on the ends of

the frame; D, depressed surfaces in imitation of the nail-grooves of a horseshoe, and E series of raised figures representing the nail-heads in the grooves. The appearance of a horseshoe is thus well counterfeited by the frame. 25

I claim—

The design herein shown and described for a purse or bag frame, consisting of a U-shaped frame having on the upper part of its face a raised figure in imitation of a toe-calk of a horseshoe, raised figures in imitation of heel-calks near the ends of the frame, depressed surfaces between the said raised figures in imitation of the nail-grooves, and raised figures in imitation of nail heads in the depressed surfaces. 30 35
